SWITCH MECHANISM FOR CONVEYING SYSTEMS

Martin J. Anderson, Ellwood City, Pa., assignor to Mathews Conveyer Company, Ellwood City, Pa., a corporation of Pennsylvania

Application April 11, 1932, Serial No. 604,380
Renewed January 11, 1935

17 Claims. (Cl. 193—36)

This invention relates to an improved switch mechanism adapted for use in connection with a conveying system, to direct articles such, for example, as metal sheets, either singly or in packs or bundles, packages, boxes, and various other articles which are to be conveyed or transported from a plurality of conveyers or stations to a single conveyer or receiving means.

An object of the invention is to provide a simple and inexpensive switch mechanism adapted to receive articles from two or more separate sources of supply and feed them onto a suitable receiving means such as a single line conveyer.

A further object is to provide a switch mechanism incorporating anti-friction wheels as a means for carrying the articles, whereby the articles may be conveyed over the mechanism with the least possible resistance, thereby providing for the transportation of articles at a greater speed than has heretofore been possible on conveyers using ordinary rollers as a conveying means.

Other objects of the invention reside in the provision of a conveyer switch mechanism of the gravity type, adapted for automatic operation, and comprising a plurality of hinged conveyer switch sections, each connected with a separate source of supply and all leading to a main line conveyer; in the means for alternately actuating said switch sections so that when one is in a raised operative position, the other will be in a lowered inoperative position, out of line of travel of the articles; in the construction of the switch sections, per se; whereby they may be moved into and out of a given plane; in the particular arrangement of the control means, including the limit switches, motor and operating mechanism; and in the general construction of the switch mechanism, as a whole, whereby it may be readily moved about from place to place by a suitable crane or other carrying device.

Other objects of the invention will appear from the following description and accompanying drawings and will be pointed out in the annexed claims.

In the accompanying drawings, there has been disclosed a structure designed to carry out the various objects of the invention, but it is to be understood that the invention is not confined to the exact features shown as various changes may be made within the scope of the claims which follow.

In the drawings:

Figure 1 is a side elevation of my improved switch mechanism;

Figure 2 is a plan view of Figure 1, the anti-friction conveyer wheels being omitted;

Figure 3 is an enlarged detail plan view of a portion of the apparatus, showing the two movable switch sections;

Figure 4 is a cross sectional view on the line 4—4 of Figure 2, showing one of the switch sections in raised operative position, and the other in a lowered inoperative position;

Figure 5 is a cross-sectional view on the line 5—5 of Figure 2;

Figure 6 is a cross sectional view on the line 6—6 of Figure 3, showing one of the switch sections in lowered inoperative position;

Figure 7 is a similar view on the line 7—7 of Figure 3, showing the other switch section in raised operative position;

Figure 8 is a cross-sectional view on the line 8—8 of Figure 2, showing the pivot about which the movable switch sections oscillate;

Figure 9 is an end view of the switch mechanism, taken on the line 9—9 of Figure 2, showing the control means provided over each conveyer section adapted to be actuated by articles traveling thereover to automatically control the operations of the switch sections;

Figure 10 is a detail sectional view on the line 10—10 of Figure 3, showing the clearance slots provided in certain rails of one of the switch sections adapted to receive the rails of the other switch section;

Figure 11 is a diagrammatic plan view showing articles being delivered over the switch mechanism;

Figure 12 is a wiring diagram showing the electrical connections between the various control devices; and

Figure 13 is a diagrammatic plan view of a switch mechanism adapted to receive articles from three separate sources of supply.

In the selected embodiment of the invention here shown, there are illustrated for purposes of disclosure, two stationary conveyer sections 2 and 3, each comprising longitudinal side rails 5 and 6 and intermediate rails 7. One end of each conveyer section is curved inwardly, as best shown in Figures 2 and 11, towards a single line conveyer 8 comprising side rails 9 and intermediate rails 11. The curved conveyer sections 2 and 3 are shown supported upon suitable structural frames, indicated generally by the numerals 12 and 13, and the single line conveyer is shown supported upon a suitable structural frame indicated by the numeral 14. Suitable anti-friction wheels 15 are mounted upon the rails 5, 6, and 7 of the con-

veyer sections 2 and 3, and also upon the rails 9 and 11 of the conveyer section 8.

An important feature of this invention resides in the means provided for conveying articles from the two conveyer sections 2 and 3 onto the single line conveyer 8, whereby the danger of the articles becoming congested at the juncture of the three conveyers is minimized.

The means provided for thus conveying the articles from the conveyers 2 and 3 onto the single line conveyer 8, comprises a switch mechanism composed of two curved conveyer sections 16 and 17, which are pivotally connected to the receiving end of the single line conveyer 8 by means of a cross shaft 18, suitably supported upon the conveyer section 8. The pivoted end portions of the switch sections 16 and 17 are substantially aligned with the single line conveyer 8 and their opposite ends are adapted for vertical movement, whereby said switch sections may be moved into and out of alignment with the discharge ends of their respective curved conveyer sections 2 and 3.

The switch section 16 is shown comprising side rails 19 and 21 and a pair of intermediate rails 22, here shown as being formed of flat or strap iron. The swinging ends of the rails 19, 21, and 22 are secured to a cross rail 23, which is movable therewith, and their opposite ends are pivotally supported upon the cross shaft 18. The switch section 17 is shown comprising side rails 24 and 25 and intermediate rails 26, all of which are shown relatively wider, vertically, than the corresponding rails 19, 21, and 22 of the switch section 16, as will readily be noted by reference to Figure 4. The rails 24, 25, and 26 of the switch section 17 have secured to their lower portions, suitable channel bars 27 which extend lengthwise thereof and are secured to a suitable cross rail 28, provided at the receiving end of the switch section. The opposite ends of the rails of the switch section 17 are pivotally supported upon the cross shaft 18, in a manner similar to the rails of the switch section 16.

Suitable anti-friction wheels 29 are mounted upon the rails 24, 25, and 26 of the two switch sections 16 and 17, as best shown in Figure 3. The vertically movable ends of the switch sections are adapted to be elevated to positions wherein the tops of the anti-friction wheels thereof will be substantially aligned with the tops of the anti-friction wheels 15 of the stationary conveyer sections 2 and 3.

In order to thus move the switch sections into and out of alignment with their respective conveyer sections 2 and 3, means must be provided whereby the longitudinally extending rails of the two switch sections will not interfere with one another, when the sections are alternately moved up and down. To thus avoid interference between the rails of the two switch sections, a plurality of notches 31 are provided in the upper edges of the rails 24, 25, and 26 of the switch section 17 adapted to receive the longitudinally extending rails 19, 21, and 22 of the switch section 16, as clearly illustrated in Figures 4 and 10. It will also be noted by reference to Figure 3, that some of the anti-friction wheels of the switch section 17 are arranged in staggered relation upon the side rails 24 and 26 in order to prevent the wheels from interfering with one another during operation of the switch sections.

Means are provided for alternately moving the switch sections 16 and 17 into and out of alignment with their complementary stationary conveyer sections 2 and 3, and as shown in Figures 6

and 7, may consist of suitable cams 32 and 33 mounted upon and secured to shaft 34 and 35, which are supported in suitable bearings 36 secured to the structural frame 13. The cams 32 and 33 are adapted to engage rollers 37, provided on the side rails of the two switch sections, as clearly shown in Figures 6 and 7. Thus, it will be seen that the weights of the vertically movable end portions of the two switch sections 16 and 17 are carried upon the peripheries of the cams 32 and 33, so that when the latter are rotated, the switch sections will be vertically moved up and down into and out of alignment with the stationary conveyer sections 2 and 3. In the particular arrangement shown, it will be noted that the cams 32 and 33 are disposed in diametrically opposite relation so that when one switch section is elevated into alignment with its respective conveyer section, the other switch section will be in a lowered inoperative position.

The means provided for driving the cam shafts 34 and 35 is best shown in Figures 1 and 3, and may consist of a drive shaft 38 supported in suitable bearings 39 secured to the structural frame 13. Bevel gears 40 are secured to the ends of the drive shaft 38, and these gears mesh with similar gears 41 secured to the cam shafts 34 and 35. The drive shaft 38 is shown driven from a suitable gear reducer 42 by means of a chain drive 43, and the gear reducer is operatively connected to a suitable motor 44 by a flexible coupling 45. From the foregoing, it will readily be understood that when the motor 44 is operating, the two cam shafts will be driven to alternately move the switch sections 16 and 17 into and out of alignment with their complementary conveyer sections 2 and 3.

The novel switch mechanism herein disclosed is adapted for automatic operation and, as shown, comprises a motor and a plurality of limit switches, some of which are adapted to be actuated by articles conveyed over the mechanism, and others by the up-and-down movement of the conveyer switch sections 16 and 17.

As best shown in Figures 1 and 9, limit switches 46 and 47 are supported over the receiving ends of the stationary conveyer sections 2 and 3, respectively, by means of suitable supports 48 and 49, secured to the structural frames 12 which support the receiving ends of the conveyer sections 2 and 3. These limit switches are of the normally open type, and are adapted to be actuated by pivoted arms 51 and 52 each carrying a roller 53 positioned to be engaged by articles traveling over the conveyer sections, as indicated by the dotted lines in Figures 1 and 9.

Similar limit switches 54 and 55 are shown situated adjacent to the conveyer switch sections 16 and 17 and, in the present case, are shown mounted directly beneath the movable switch sections, as best shown in Figure 4. Each of said switches has an arm 57 carrying a roller 58 as shown in Figure 12. The roller of the switch 55 is adapted to be engaged by a depending bracket 59 provided upon the switch section 16, and the roller 58 of the switch 54 is adapted to be engaged by a member 61 provided upon the switch section 17. The limit switches 54 and 55 are of the normally closed type. Actuation of the limit switches 46, 47, 54, and 55 controls the operation of the motor 44 which operates the cam shafts 34 and 35.

In the wiring diagram, Figure 12, I have shown a motor of the reversible type comprising two main control switches 62 and 63. The switch 62

comprises the usual fixed contacts 64, 65, and 66 connected to the main line conductors 67, 68, and 69 by suitable wires 71, 72, and 73. The fixed contacts of the switch 62 are adapted to be electrically engaged by a plurality of movable contacts 74, 75, and 76 having wires 73, 79, and 81 leading therefrom to the motor 44. An actuator 82 is operatively connected to the movable contacts of the switch 62 and is adapted to be actuated by a solenoid coil 83, having a wire 84 connecting one end thereof to a movable contact 85 of the limit switch 46. A wire 86 connects the other end of the coil 83 to the fixed contact 87 of the limit switch 54. The movable contact 88 of the limit switch 54 has a wire 89 connecting it to the main line conductor 68.

The fixed contact 91 of the limit switch 46 is connected by a wire 92 to the main line conductor 69, and a wire 93 leads from the movable contact 85 of the limit switch 46 to a fixed contact 94, adapted to be engaged by movable contact 95 which is operatively connected to the actuator 82, as shown. A wire 96 is shown connecting the movable contact 95 with the movable contact 76 of the motor switch 62.

The other motor switch 63 is shown comprising fixed contacts 97, 98, and 99, and wires 101, 102, and 103 are shown connecting them respectively, to the wires 71, 72, and 73 of the motor switch 62. The fixed contacts of the motor switch 63 are adapted to be electrically engaged by movable contacts 104, 105, and 106, having wires 107 and 108 and 109 connecting them to the wires 81, 79, and 78, leading from the motor switch 62 to the motor.

An actuator 111 is operatively connected to the movable contacts of the motor switch 63 and is adapted to be actuated by a solenoid coil 112, having a wire 113 connecting one end thereof to the movable contact 114 of the limit switch 47. A wire 115 connects the opposite end thereof to the movable contact 116 of the limit switch 55. The fixed contact 117 of the limit switch is connected by a wire 118 to the main line conductor 68.

The limit switch 47 has a fixed contact 119 which is electrically connected by a wire 121 to the main line conductor 69. The movable contact 114 of the switch 47 has a second wire 122 connecting it to a fixed contact 123 adapted to be engaged by a movable contact 124 shown electrically connected to the movable contact 125 of the motor switch 63 by a wire 125. The movable contact 124 is adapted to be actuated by the actuator 111.

To prevent overrunning of the motor when the supply of current thereto is interrupted, a suitable magnetic brake, indicated by the numeral 126, is operatively associated with the motor 44 and is adapted to be actuated by a spring 130, and a solenoid coil 127 having wires 128 and 129 here shown connecting it to the wires 79 and 81 of the motor circuit. The brake 126 has an arm 131 to the outer end of which is connected an armature 132 adapted to be actuated by the solenoid 127. The brake 126 is normally set by the action of the spring 130, and is released when the solenoid 127 is energized, as will subsequently be described.

Operation

When the novel switch mechanism herein disclosed is employed for transporting sheet metal plates from two or more furnaces to a rolling mill, it is interposed between the discharge ends of the

furnaces and the receiving end of the rolling mill as diagrammatically illustrated in Figure 11. When a sheet is discharged from furnace A, as shown in Figure 11, it will engage the roller 53 of the arm 51 of the limit switch 46 and cause the latter to oscillate so that a cam 50 provided at the upper end of the arm will actuate the limit switch 46 and cause it to close. When this switch is closed, a circuit is completed through the solenoid 83 as follows: wire 92, closed limit switch 46, wire 84, solenoid 83, wire 86, normally closed limit switch 54, and wire 89. The wires 92 and 89 are connected to the main line.

When the solenoid 83 is energized, the actuator 82 will be operated to close the motor switch 62, whereupon the motor will operate to rotate the cams 32 and 33 assuming, of course, that the switch section 16 is in a lowered position. Should the switch section 16 be in an elevated position and the switch section 17 in a lowered position, the circuit to the solenoid 83 cannot be completed because the limit switch 54 will then be held open by the member 61 of the switch section 17. If, on the other hand, the switch section 16 is in a lowered position and the switch section 17 is in its raised position, the circuit through the solenoid 83 will be completed so that the latter will be energized and operate the motor switch 62. As soon as the cam shafts 34 and 35 have been rotated 180°, the member 61 of the switch section 17 will engage and open the limit switch 54, whereupon the supply of current to the solenoid 83 will be cut off and the motor switch 62 will return to its normal open position, with the resultant interruption of the motor. The movable contacts of the motor switch 62 may be returned to their normal open positions by means of gravity or by suitable springs, not shown.

It will thus be seen that if the sheets continue to discharge from the furnace A, the motor will remain at rest and the switch section 16 will be retained in its raised operative position in registration with the conveyer section 2. Each time the limit switch 46 is closed by reason of a sheet or article actuating the arm 52 thereof, a circuit is presented to the solenoid 83, but as long as the switch section 17 is in its lowered position, the limit switch 54 will be held open by the member 61 so that the circuit to the solenoid 83 cannot be completed.

Should a sheet be discharged from the furnace B onto the conveyer section 3, then the limit switch 47 over said conveyer section will be closed because of the sheet oscillating the arm 52 thereof. The closing of the limit switch 47 will complete a circuit to the solenoid 112 because of the limit switch 55 beneath the switch section 16 being in closed position, when said switch section 16 is in its raised operative position. The circuit through the solenoid 112 will be as follows: from the main line conductor 69 through the wire 121, limit switch 47, wire 113, solenoid 112, wire 115, through the closed contacts of the limit switch 55, and thence through the wire 118 to the main line conductor 68. At the instant that the solenoid 112 becomes energized, the actuator 111 of the motor switch 63 will operate and close said switch, whereupon the motor will be operated in reverse direction until the cam shafts 34 and 35 have been rotated 180°, at which time the bracket 59 on the switch section 16 will engage and open the limit switch 55, thereby breaking the circuit to the solenoid 112, whereupon the actuator 111 will open the motor switch 63 and cause interruption of the motor. It is to be

understood that the magnetic brake 126 is released when the solenoid 127 is energized and pulls the arm 131 downwardly. When current flow through the solenoid 127 is interrupted, the 5 brake will automatically be set by the action of the spring 130, as is well known.

It will thus be seen that the operation of this 10 novel conveyer switch mechanism is entirely automatic, and the arrangement of the limit switches is such that if the sheets or articles are alternately delivered to the switch sections 16 and 17 from the separate sources of supply, the motor will continuously operate to raise and lower the switch sections, so that whenever an 15 article fed from one of the conveyer sections 2 or 3 onto a switch section, the particular switch section connected therewith will automatically raise into registration with said conveyer section so that the articles may pass uninterruptedly 20 over the switch section to the receiving means 8. It will also be noted that if the articles are continuously delivered to one conveyer section, as for example section 2, then the switch section 16 will be retained in alignment therewith so as to 25 present an unbroken path to articles traveling over the apparatus from the furnace A to the receiving means, or rolling mill.

The apparatus, as shown in the drawings, particularly Figures 1 and 5, is constructed as a 30 unit so that it may readily be moved about from place to place. To thus construct the apparatus, the structural frames 12, 13, and 14 are shown mounted upon a suitable sub-frame 132, comprising a pair of beams 133 connected together 35 by suitable cross members 134 and 135 provided at the ends of the structure, and a plurality of intermediate cross members, shown in Figure 2, and upon which the motor and driving mechanism may be supported. Suitable lifting bars 40 136 and 137 are provided adjacent the ends of the structure having apertures 138 and 139 therein, respectively, adapted to be engaged by suitable hooks 141 of a plurality of lifting chains 142, partially indicated in Figures 1, 5, and 9. By thus 45 constructing the apparatus, it may readily be moved about from place to place by means of a crane or other suitable lifting device.

In Figure 13, I have shown a switch mechanism 50 adapted to receive articles or plates from three separate sources of supply such, for example, as furnaces A, B, and C. As here shown, the switch sections 2a and 3a correspond to the switch sections 2 and 3 shown in Figure 11 and, in like manner, the conveyer section 8a corresponds to the 55 similar switch sections 8, shown in Figure 11. Aligned with the conveyer section 8a is a curved conveyer section 143 which is adapted to receive articles from the conveyer section 8 and deliver them to a switch section 16a arranged adjacent to the rolling mill in a manner similar to that shown 60 in Figure 11. A similar curved conveyer section 144 connects the switch section 16a at the right hand side of Figure 13, with a conveyer section 145 which has its receiving end positioned to receive plates from the third furnace C.

By thus arranging the switch sections 16 and 17, and 16a and 17a, an apparatus is provided 70 which is adapted to receive from three separate sources of supply. It is also to be noted that the two switch mechanisms employed in the structure, may be of like construction, and the control or limit switches provided may be arranged in substantially the same manner as those shown in Figure 11, and their functions will be substantially 75 the same.

When plates are being discharged from furnace A, the switch sections 17 and 17a will be retained in their lower inoperative positions so that plates traveling from furnace A to the rolling mill, may pass uninterruptedly over the apparatus. Should a plate be discharged from furnace B, switch 47 5 will be actuated to cause the switch section 17 to move into operative position whereby the switch section 16 will be lowered to its inoperative position. The plates may then be transferred from furnace B over the switch section 17 and switch section 16a to the rolling mill, it being understood 10 that switch section 16a will be retained in operative position until the limit switch 47a is actuated. When a plate is discharged from furnace C, it will travel over the conveyer section 145 and engage limit switch 47a which will cause the switch section 17a to be moved into operative position, whereby the adjacent switch section 16a 15 will be lowered to its inoperative position. It will thus be seen that by arranging two sets of 20 switch mechanisms, as shown in Figure 13, an apparatus is provided which will receive plates or articles from three separate sources of supply and deliver them to a single receiving means. 25

In the drawings I have shown the apparatus adapted for use to transfer sheets from either side of a continuous double heating furnace to a finishing mill for finish-rolling thin sheet metal plates. The sheets are never discharged from 30 both sides A and B of the furnace at the same time, but are discharged either alternately from both sides of the furnace, or continuously from one side thereof, and in spaced relation, so that but one sheet or article is delivered to the switch 35 sections 16 and 17 at a time. Obviously, the apparatus may be used for various other purposes when applicable. It is also to be understood that the operating mechanism for raising and lowering the switch sections 16 and 17 may be 40 varied without departing from the scope of the invention. In some cases, it may also be found desirable to dispense with the stationary conveyer sections 2 and 3 and lengthen the switch sections 16 and 17 so that the articles may be 45 delivered directly thereto from the delivery means. The receiving conveyer section 8 may also be dispensed with in some installations. It is also to be understood that a non-reversible motor may be used in lieu of the reversible type 50 motor shown.

In the drawings I have shown the apparatus arranged for transporting articles from separate sources of supply to a single receiving means. It is to be understood, however, that by reversing 55 the inclination of the apparatus from that shown in Figure 1, the movement of the articles over the apparatus may be reversed, that is, articles may then be fed from the conveyer 8 onto the conveyer sections 2 and 3.

I claim as my invention:

1. In an apparatus of the class described, a plurality of stationary conveyer sections, vertically movable conveyer sections longitudinally aligned with said stationary sections and converging therefrom to a single receiving means, and means for simultaneously actuating said movable sections to cause them to move into and out of registration with their respective stationary sections. 65
2. In an apparatus of the class described, a plurality of stationary conveyer sections, vertically movable conveyer switch sections longitudinally aligned with said stationary sections and converging therefrom to a single receiving means, 70
3. In an apparatus of the class described, a plurality of stationary conveyer sections, vertically movable conveyer switch sections longitudinally aligned with said stationary sections and converging therefrom to a single receiving means, 75

and interconnected means for simultaneously actuating said movable sections to cause them to alternately move into and out of registration with their respective stationary conveyer sections.

5 3. In an apparatus of the class described, a plurality of movable switch sections adapted to receive articles from separate sources of supply, said movable switch sections converging to a single receiving means whereby all articles received by said sections will be delivered to said receiving means, and means for raising and lowering the receiving ends of said switch sections to control the movement of articles traveling thereover.

10 4. In a switch mechanism of the class described, a plurality of stationary conveyer sections, pivoted conveyer switch sections leading from said stationary conveyer sections to a single conveying means, mechanism for alternately raising and lowering said switch sections into and out of registration with said stationary conveyer sections, a driving means for said mechanism, and means positioned to be actuated by articles traveling over said stationary conveyer sections to control the operation of said driving means.

15 5. In a switch mechanism of the class described, a plurality of stationary conveyer sections, pivoted switch sections leading from said stationary conveyer sections to a single conveying means, mechanism for alternately raising and lowering said switch sections into and out of registration with said stationary conveyer sections, a driving means for said mechanism, and means for automatically controlling the operation of said driving means, comprising a plurality of electric switches electrically connected with said driving means, and certain of said switches being positioned to be actuated by articles delivered to said stationary conveyer sections.

20 6. In a switch mechanism of the class described, a plurality of conveyer switch sections having their discharge ends converging to a single receiving means, mechanism for alternately raising and lowering said switch sections into and out of operative positions in a given plane, a driving means for said mechanism, an electric switch at the receiving end of each conveyer switch section provided with means adapted to be engaged by articles passing over said switch sections to thereby actuate said switches, other electric switches electrically associated with said first-mentioned switches and adapted to be opened and closed when said conveyer sections are moved up and down, and all of said electric switches being operatively associated with said driving means and so arranged that when an article is to be delivered to a selected conveyer switch section, said electric switches will cooperate to cause said driving means to operate and move said selected switch section into load receiving position.

25 7. In a switch mechanism of the class described, a supporting structure, a plurality of stationary conveyer sections at one end thereof and a single conveyer section at the opposite end thereof, movable conveyer switch sections connecting said stationary conveyer sections with said receiving section, mechanism for alternately raising and lowering said switch sections into and out of registration with their respective conveyer sections, a motor for operating said mechanism, a normally open limit switch over each stationary conveyer section having means normally positioned in the path of articles traveling over said conveyer sections, a normally closed limit switch positioned adjacent to each conveyer switch section,

means adapted to open said second mentioned limit switches when their respective conveyer switch sections are in lowered position, and all of said limit switches being interconnected with the motor circuit and adapted to automatically control the operation of the motor when articles are traveling over said switch mechanism.

30 8. In a switch mechanism of the class described, a plurality of stationary conveyer sections, conveyer switch sections longitudinally aligned with said stationary conveyer sections and converging to a single receiving means, mechanism for alternately raising and lowering said switch sections into and out of registration with their respective stationary conveyer sections, a driving means for said mechanism including an electric motor, a normally open limit switch over each stationary conveyer section provided with means adapted to be engaged by articles passing over said conveyer sections to automatically close said limit switches, a normally closed limit switch adjacent to each conveyer switch section, said normally closed switches having means adapted to be actuated by downward movement of their respective conveyer switch sections to temporarily close said limit switches, and said limit switches being electrically associated with the motor circuit and so arranged that when an article is delivered to a selected stationary conveyer section, the limit switches associated therewith will cooperate to control the operation of said motor and cause the conveyer switch section aligned with said selected conveyer section to move into registration so that the article may pass uninterruptedly over said switch mechanism onto the receiving means.

35 9. In an apparatus of the class described, a plurality of curved switch sections adapted to receive articles from separate sources of supply and deliver them to a common receiving means, each switch section comprising spaced rails having anti-friction wheels mounted thereon, and the rails of one section being disposed in intersecting relation to the rails of another section, operating means for alternately raising and lowering said switch sections into and out of a given plane to receive and carry a load, and a plurality of control devices cooperating to automatically control the operation of said operating means, certain of said control devices being positioned to be actuated by articles passing over the apparatus, and others being positioned to be actuated by said switch sections, when vertically moved.

40 10. In an apparatus of the class described, a plurality of curved switch sections adapted to receive articles from separate sources of supply and deliver them to a common receiving means, said sections being pivotally mounted at one end, each section comprising a plurality of spaced rails having anti-friction wheels mounted thereon, and the rails of one section being disposed in intersecting relation to the rails of another section, operating means for alternately raising and lowering the free ends of said switch sections into and out of a given plane to receive and carry a load, and a plurality of control devices cooperating to automatically control the operation of said operating means, certain of said control devices being positioned to be actuated by articles passing over the apparatus, and others being positioned to be actuated by said switch sections, when vertically moved.

45 11. In an apparatus of the class described, a plurality of vertically movable switch sections

adapted to receive articles from separate sources of supply, said movable switch sections converging to a single receiving means whereby all articles fed onto said sections may be delivered 5 to said receiving means, operating means for actuating said switch sections to selectively move them into operative positions with said receiving means, and a control mechanism for said operating means comprising a plurality of elements operatively associated therewith and adapted 10 to be actuated by articles traveling over the apparatus.

12. In an apparatus of the class described, a plurality of vertically movable switch sections, 15 a single conveyer connected to said switch sections, operative means for simultaneously actuating said movable switch sections to cause them to alternately move into and out of operative positions, and a plurality of elements operatively 20 associated with said operating means and positioned to be engaged by articles delivered to said switch sections whereby said elements will be actuated by the articles and thereby control the movement of said switch sections.

25. 13. In an apparatus of the class described, a plurality of vertically movable switch sections spaced apart at one end of the apparatus and converging to a single receiving means at the opposite end thereof, a mechanism for actuating 30 said movable switch sections to cause them to alternately move into and out of operative positions, and means positioned to be actuated by articles passing over said apparatus to control the operation of said mechanism.

35. 14. In an apparatus of the class described, a plurality of movable switch sections spaced apart at one end of the apparatus and converging to a single receiving means at the opposite end thereof, a mechanism for moving said switch sections 40 into and out of operative positions, and means for automatically controlling the operation of said mechanism, comprising a plurality of con-

trol elements, certain of which are positioned to be actuated by articles delivered onto the apparatus.

15. In an apparatus of the class described, a plurality of movable switch sections spaced apart at one end of the apparatus and converging to a single receiving means at the opposite end thereof, a mechanism for moving said switch sections into and out of operative positions, and means for automatically controlling the operation of said mechanism, comprising a plurality of control elements, certain of which are positioned to be actuated by articles delivered onto the apparatus, and others of which are actuated by movement of said switch sections. 15

16. In an apparatus of the class described, a plurality of movable switch sections spaced apart at one end of the apparatus and converging to a single receiving means at the opposite end thereof, a mechanism for imparting up-and-down movements to said switch sections to move them into and out of operative positions, and a control means associated with said mechanism and made operable by articles delivered onto the apparatus, to thereby automatically control the operation of 25 said mechanism.

17. In an apparatus of the class described, a plurality of movable switch sections spaced apart at one end of the apparatus and converging to a single receiving means at the opposite end thereof, a mechanism for imparting up-and-down movements to said switch sections to move them into and out of operative positions, and a control means associated with said mechanism and made operable by articles delivered onto the 30 apparatus, to thereby automatically control the operation of said mechanism, said control means comprising a plurality of interconnected control elements, certain of which are positioned to be engaged by the articles. 35

MARTIN J. ANDERSON. 40.
